UNITED STATES PATENT OFFICE

FREDERIC C. HOOD, OF BROOKLINE, MASSACHUSETTS, ASSIGNEE, BY MESNE ASSIGNMENTS, TO HOOD RUBBER COMPANY, INC., OF WILMINGTON, DELAWARE, A CORPORATION OF DELAWARE

BUCKLE

Application filed February 16, 1929. Serial No. 340,585.

This invention relates to an improved buckle adapted for use on footwear, and particularly on overshoes in which the opposite edges of the quarter are joined together by a strap projecting over the vamp.

The object of the invention is to provide a buckle simple in construction, cheap in its manufacture, and neat in its appearance, very little of the buckle being seen when it is in operative position.

The buckle of this invention embodies two parts, one of which has a hook thereon which projects into an orifice provided in the other part.

15 The invention consists in a buckle of the character set forth in the following specification and particularly pointed out in the claim.

Referring to the drawings:

Figure 1 is a perspective view of a portion 20 of an overshoe illustrating the buckle of my invention attached thereto.

Fig. 2 is an enlarged sectional view taken on the line 2—2 of Fig. 1 and viewed in the direction of the arrows on said line.

25 Fig. 3 is a perspective view of one portion of the buckle taken from the rear side.

Fig. 4 is a perspective view on an enlarged scale of the other part of the buckle, taken from the front side.

30 Fig. 5 is a perspective view on an enlarged scale of a modified form of the hook portion of my invention.

Like numerals refer to like parts in the views of the drawings.

35 The buckle of this invention comprises two parts, one of the parts 8 illustrated in Figs. 1, 2 and 3 embodying a plate 9 with a hook 10 rigidly affixed thereto and projecting from the rear face of the plate 9. The hook com-

40 prises a shank 11 and a prong 12, the prong being bevelled toward the point thereof on its inner face 13 and at 14 on its outer face. The plate 9 is provided with slots 15 and 16 through which a strap 17 projects. The

45 strap 17 is fastened at one end to the inner portion of a quarter 18 and the plate 9 is adjustable on the strap 17.

The other part 19 of the buckle is illustrated in Figs. 2 and 4 and comprises a plate embodying two end flanges 20 and 20' and a

raised central portion 21 which is joined to the flanges 20 and 20' by shoulders 22, 23 and 24. The raised portion 21 is provided with a V-shaped orifice 25 which is prolonged rearwardly at 26 between the shoulders 22 and 23. The part 19 is fastened to the quarter 18 by rivets 27 as illustrated in Fig. 2.

The two parts of the buckle are joined together for use as particularly illustrated in Fig. 2, the part 19 being mounted on the strap

17. The strap 17 is drawn across the vamp 28 as illustrated in Fig. 1 and the hook 10 inserted in the orifice 25 and drawn forwardly into said tapered orifice. During this opera-

55 tion the bevelled inner face 13 engages the inner face of the raised portion 21 of the part 19 and thus the plate 9 and the raised portion 21 are drawn closely together as seen in Fig. 2.

The bevelled portion 14 on the rear face of the hook 10 prevents abrading the cloth of the quarter 18. Also, as the hook is drawn up

50 into the wedge-shaped orifice 25, the opposite edges of said orifice will bear against the shank 11 and hold the two parts firmly engaged one with the other.

Furthermore it will be seen that it is not necessary in positioning the hook 10 within the orifice 25 to be very exact about such pos-

itioning operation, as the hook may enter the orifice 25 through the opening 26 at the rear end thereof and then be brought forward into the orifice, or if it is pushed downwardly at

65 the rear end thereof, there will be consider-

able space between the hook and the opposite edges of the orifice so that it is very easy

70 to engage the two parts of the buckle one with the other and as this operation is performed while the user is leaning over, this is an essen-

75 tial and very desirable feature of the invention. The parts of the buckle of this inven-

80 tion are not only easily connected together, but they are also easily disconnected from each other.

In Fig. 1 the overshoe is illustrated as having a collar 29 which, in the illustration, is shown turned up at 29' for the purpose of disclosing the buckle and strap, but when in use, the portion 29' of the collar is turned down and covers the buckle and the portion of the strap 17 adjacent thereto.

The modification of my invention illustrated in Fig. 5 embodies a plate 9' with slots 15' and 16' in its opposite ends respectively and a hook 10' consisting of a wedge-shaped 5 prong 12' and a shank 11'. In this embodiment of my invention the hook is formed of material which is died out of the plate 9', thus providing an opening 30 through the plate 9'. The manner of use of this modification 10 of my invention is the same as hereinbefore described in that form of my invention illustrated in Figs. 1 to 4 inclusive.

I claim:

A buckle in two parts, one of said parts embodying a plate and a hook projecting from one face thereof, the other of said parts embodying a plate comprising a flange, a raised portion and a shoulder connecting the flange to the raised portion, said raised portion and shoulder being formed with an orifice having a portion of enlarged area in the shoulder and a portion of reduced area in the raised portion, enabling said hook to be inserted bodily into the enlarged portion of said orifice by 15 relative movement if said plates either in a direction substantially parallel or in a direction substantially normal to each other, and enabling said hook to be positioned for engagement in the portion of reduced area of 20 said orifice by further relative movement of 25 said plates.

In testimony whereof I have hereunto set my hand.

FREDERIC C. HOOD.
